MACHINE FOR USE IN APPLYING HEELS TO
SHOES

Edward H. Bastable, Clifton, Mass.

Application January 3, 1938, Serial No. 183,040

5 Claims. (Cl. 12—1)

This invention relates to the manufacture of shoes and more particularly to a machine or apparatus for use in applying a clamping member to an assembled heel and lasted shoe.

5 In accordance with conventional shoe-making practices, the heels are often secured to the heel-seat surface of the lasted shoe by a layer of suitable cementitious material which, if desired, may be supplemented by metallic fastening elements 10 usually applied after the cementitious material has become set. Regardless of the type of adhesive or cement employed, it is necessary that the lasted shoe and heel be maintained relatively immovable during the period required by the cement to become thoroughly set. To this end it has been proposed to apply various types of clamping means such, for example, as a heavy elastic band about the heel and lasted shoe so as to hold the parts firmly in assembled relation. 15 Such clamping means are quite difficult to apply and furthermore the application not only involves the danger of mispositioning the heel, but also of smearing the exposed parts of the heel and upper with cement.

20 The principal objects of the present invention are to provide a machine capable of expanding an elastic band or the like expansible clamping device so that the band or clamping device may be quickly and accurately applied about the assembled heel and lasted shoe by an inexperienced operator without danger of mispositioning the parts; and to provide a machine which is of simple construction, having but few parts, which is reliable and efficient in operation, and which can 25 be manufactured at a relatively low cost.

25 Further objects will be apparent from a consideration of the following description and the accompanying drawings, wherein

30 Fig. 1 is an elevational view of a machine constructed in accordance with the present invention;

35 Fig. 2 is a fragmentary sectional elevation of the principal operating parts of the machine shown in Fig. 1;

40 Figs. 3, 4 and 5 are views showing different types of expansible clamping means for holding the heel and lasted shoe in assembled relation;

45 Fig. 6 is an enlarged perspective view of an adapter device for use in conjunction with an elastic band or the like clamping member;

50 Figs. 7 and 8 are fragmentary side elevations showing different types of clamping members and adapter devices applied to an assembled heel and lasted shoe;

Figs. 9 and 10 are views showing other modified types of clamping members; and

Fig. 11 is a perspective view of an adjunct used in applying clamping members of the type shown in Figs. 8 to 10.

The embodiment chosen for illustration comprises an upstanding hollow post or pedestal 1 (Fig. 1) having at its lower end an opening 2 through which projects a depressible treadle 4 pivoted within the pedestal in any conventional manner. The upper end of the pedestal supports a casing or housing 5 (Figs. 1 and 2) formed with a substantially rectangular opening 6 in its front wall 7. A substantially rectangular frame-like member 10, formed integral with or rigidly secured to the interior of the housing, defines a chamber for the reception of an assembled heel and lasted shoe. The bottom wall of the housing 5 is provided with an opening which receives an upstanding support 11 having at its upper end a pin 12 adapted to be inserted in the usual hole formed in a last so as to hold the last in fixed position within the housing. The lower end of the support 11 is rigidly secured in position by a set screw 13 which, if desired, may be loosened to permit the removal of one support and the substitution of another. The frame 10 is formed with a pair of upper and lower vertically extending slots 14 and 15, the lower slots being at approximately the same level as the top of the support 11.

Arms 16, 17, 18 and 19 are pivotally supported on transversely extending shafts 20, 21, 22 and 23, respectively, which are secured to the front and rear walls of the housing 5, the arms 16 and 17 extending through the upper slots 14 and the lower arms 18 and 19 extending through the lower slots 15, as shown in Fig. 2. The ends of the arms are formed or otherwise provided with forwardly extending fingers 24, 25, 26 and 27 disposed in pairs about or on opposite sides of the support 11. The opposite ends of the arms 16—19 carry segmental gears 30, 31, 32 and 33, respectively, the gears 30, 32 and 31, 33 being arranged to provide interengaging pairs, as shown in Fig. 2. Although the gears 30—33 may, if desired, be of the same size (that is, have the same teeth ratio) so as to effect the same angular movement of their associated arms, they are preferably designed so that the angular movement of the upper arms 16 and 17 is considerably greater than that of the lower arms 18 and 19, and to this end the ratio of teeth of gears 32, 33 to gears 30, 31 is of the order of 2 to 1.

An actuating rod 35 (Fig. 2) extends longitudi-

nally within the pedestal 1 and adjacent to its upper end this rod is slidably supported by a bearing 36 formed in the bottom wall of the housing. The rod 35 extends upwardly beyond the bottom wall of the housing to a point beneath the frame 10 which provides, in effect, a stop limiting its upward movement. The lower end of the rod 35 is pivotally connected to the treadle 4 in any conventional manner so as to be moved downwardly when the treadle is depressed, it being understood that a coil spring or the like (not shown) may be provided to effect the return movement of the rod 35 and associated parts. The upper end of the rod 35 carries a transversely extending beam 38, the opposite ends of which project laterally beyond the sides of the frame 10, and links 40 and 41 are pivotally connected to the ends of the beam and to the lower arms 18 and 19 at points 42 and 43, respectively.

20 The parts are so constructed and arranged that the fingers 26 and 27 are normally disposed on each side of and at substantially the same horizontal level as the support 11, and the fingers 24 and 25 are disposed on each side of the vertical line of the support 11, but at a substantial distance above the same, as shown in Fig. 1. When the treadle 4 is depressed, carrying the rod 35 and associated parts downwardly, the arms 18 and 19 are swung downwardly so that the fingers 26 and 27 are disposed adjacent to the lower part of the frame 10, and the arms 16 and 17 are simultaneously swung upwardly so that the fingers 24 and 25 are disposed adjacent to the upper part of the frame 10, as shown by the dot and dash lines of Fig. 2.

The machine herein shown is particularly suitable for use in applying an expandable, self-contractible clamping member to an assembled heel and lasted shoe. A clamping member of this type 40 may consist of a heavy rubber band 45, as shown in Fig. 3, or a coil spring 46 whose ends are secured together to form a circular band, as illustrated in Fig. 4. If desired, a clamping member such as is shown in Fig. 5, may be employed, 45 which comprises a pair of spaced jaws 50 and 51, slidably supported by a pair of bolts 52 and 53 carrying springs 54 and 55 between their heads and the upper jaw 50. The jaws 50 and 51 are preferably formed with offsets 56 and 57 shaped to receive the heel and edge of the last.

50 Where a clamping member such as is illustrated in either Figs. 3 or 4 is to be used, it is advisable, if not necessary, to employ an adapter device such as is shown in Fig. 6, in order to prevent the band from slipping off or becoming accidentally mispositioned about the assembled heel and lasted shoe. The adapter device 60 comprises a length of steel having one end 61 shaped to engage the tread of a heel and its 55 opposite end 62 shaped to engage the rear surface of the heel, the intermediate portion 63 being recessed to receive the clamping member. In order to prevent scarring the surface of the heel, the end 62 may be provided with a rubber or felt pad 65 which also serves to enhance the frictional grip of the adapter on the heel.

When using a machine constructed in accordance with the present invention for applying a clamping member of the type herein shown to 70 an assembled heel and lasted shoe, the clamping member, such as a band 45, is positioned about the fingers 24-27; meanwhile a heel 70 is positioned against a cementitious layer applied to the heel seat surface of a lasted shoe 71, and the 75 adapted 60 is then applied in the manner shown

in Fig. 7. The operator then inserts the assemblage through the opening 6 of the housing 5 and at the same time depresses the treadle 4, thus causing the band 45 to expand, as illustrated by the dot and dash lines of Fig. 2. The assemblage is positioned on the support 11 and the pressure on the treadle is gradually reduced so as to permit the band to contract about the lasted shoe 71, 72 and the recessed portion 63 of the adapter 60, as shown by the full lines of Fig. 2, 10 thus firmly clamping the heel and lasted shoe in proper position. The assemblage may then be withdrawn from the housing, care being taken to prevent the fingers 24-27 from accidentally mispositioning the band 45. After having withdrawn the assemblage from the housing, it may be put aside for a time sufficient to permit the cementitious material to become thoroughly set, after which the band may be removed either by hand or by using the machine herein shown. 20

When using a clamping member such as is illustrated in Fig. 5, the use of an adapter device may be dispensed with where, as is preferred, such clamping member is designed to extend about the heel and edge of the last 72; otherwise the 25 clamping member may be applied in a manner similar to that of the clamping bands 45 and 46. In either case such a clamping member may be inserted within the housing so that the fingers 24-27 are operative to expand the jaws 50 and 51 when the treadle 4 is depressed, the remainder 30 of the operation being the same in all material particulars as that above described.

Referring to Figs. 8 to 10, the clamps shown therein each comprises a length of heavy spring 35 74 bent to provide an approximately C-shaped member having at one end a corrugated foot 75 adapted to engage the heel 70 of the lasted shoe, and at its opposite end a conical-shaped element 76 adapted to be inserted in the spindle hole of the last 72. In order to enhance the resiliency 40 of the clamp, the wire 74 may be bent to form either an intermediate loop 78, as shown in Fig. 8, or an intermediate U-shaped portion 79, as shown in Fig. 9, although it is to be understood that, if desired, such parts may be eliminated, as shown 45 in Fig. 10. In any event, it is desirable to provide a heel-positioning member 80 (Fig. 8) effective to hold the heel 70 in proper position. As here shown, the positioning member 80 consists of a collar 81 disposed about the upper 50 section of the clamp 74, a thumb screw 82 carried by the collar 81 and engageable with the wire 74 to hold the collar in any desired position of longitudinal adjustment, and a positioning finger 84 55 carried by the collar and engageable with the outer face of the heel 70, as shown in Fig. 8.

In order to apply a clamp of the type shown in Figs. 8 to 10 to an assembled heel and lasted shoe, using a machine of the type shown in Figs. 1 and 2, a pair of adjuncts 85 (Fig. 11) is preferably used, each adjunct comprising a rigid metal strip 86 having an elongate slot 87 formed in its body portion and a centrally disposed recess 88 in one edge. 60

When using clamps of the type shown in Figs. 8 to 10, a pair of adjuncts 85 are inserted through the opening 6 of the housing (Fig. 1), one of the adjuncts being fitted so that the fingers 24, 25 extend through its slot 87 with its recessed edge uppermost, and the other adjunct being similarly fitted to the lower fingers 26, 27 with its recessed edge lowermost. When thus positioned, a clamp 70 may be applied with its upper and lower sections fitting into the recesses 88 which hold it from 75

slipping, and the treadle 4 of the machine may then be depressed to effect an extension of the clamp sufficient to permit an assembled heel and lasted shoe to be positioned on the support 11, as previously described. The positioning finger 84 may then be properly adjusted, the pressure on the treadle released, and the assemblage withdrawn from the housing, it being understood that when the treadle is released, the adjuncts 85 are carried toward each other sufficiently to permit their removal from about the fingers 24—27 and thus permitting removal of the clamp and the assembled heel and shoe.

While I have shown and described one desirable embodiment of the invention, it is to be understood that this disclosure is for the purpose of illustration and that various changes in shape, proportion and arrangement of parts, as well as the substitution of equivalent elements for those herein shown and described, may be made without departing from the spirit and scope of the invention as set forth in the appended claims.

I claim:

1. A machine of the class described comprising a support adapted to receive and hold in fixed position an assembled heel and lasted shoe, a plurality of relatively movable fingers disposed in spaced relation about said support, and means for effecting relative movement of said fingers in a direction away from each other and away from said support, said fingers normally being arranged to fit within and support an expandible, self-contractible, clamping member so as to cause the clamping member to expand to an extent sufficient to permit an assembled heel and lasted shoe upper to be positioned on said support.
2. A machine of the class described comprising an upstanding support adapted to receive and hold in fixed position an assembled heel and lasted shoe, a pair of relatively movable arms disposed on each side of said support, each of said arms having fingers normally arranged to be inserted within the confines of an expandible clamping member, and means for effecting relative movement of said arms so as to cause said fingers to expand said clamping member to an

extent sufficient to permit an assembled heel and lasted shoe to be positioned on said support.

3. A machine of the class described comprising an upstanding support adapted to receive and hold in fixed position an assembled heel and lasted shoe, a pair of relatively movable arms disposed on each side of said support, each of said arms having fingers normally arranged to be inserted within the confines of an expandible clamping member, a depressible operating lever, and connections between said arms and operating member operative to effect relative movement of said arms when said lever is depressed, thereby to expand said clamping member.

4. A machine of the class described comprising a housing having an opening through which an assembled heel and lasted shoe may be inserted, a support within said housing for holding the assembled heel and lasted shoe in fixed position, a plurality of relatively movable fingers disposed within said housing and in spaced relation about said support, means for effecting relative movement of said fingers in a direction away from each other and away from said support, said fingers normally being arranged to fit within and support an expandible clamping member so as to expand said clamping member to an extent sufficient to permit an assembled heel and lasted shoe to be positioned on said support.

5. A machine of the class described comprising a housing having an opening through which an assembled heel and lasted shoe may be inserted, a support within said housing for holding the assembled heel and lasted shoe in fixed position, a pair of relatively movable arms pivotally mounted within said housing and disposed on each side of said support, each of said arms having fingers normally arranged to be inserted within the confines of an expandible clamping member, and means for effecting relative movement of arms so as to cause said fingers to expand a clamping element carried thereby to an extent sufficient to permit an assembled heel and lasted shoe to be positioned on said support.

EDWARD H. BASTABLE.
